(57) **CLAIM**

The ornamental design for a back pressure point massage device, as shown and described.

DESCRIPTION

FIG. 1 is a top perspective view of a back pressure point massage device showing my new design;
 FIG. 2 is a front elevation view thereof;
 FIG. 3 is a top plan view thereof;
 FIG. 4 is a rear elevation view thereof;
 FIG. 5 is a bottom plan thereof;
 FIG. 6 is a left side elevation view thereof; and,
 FIG. 7 is a right side exploded elevation view thereof.
 The claimed design is shown with a symbolic break in its length, the appearance of any portion of the article between the break lines forms no part of the claimed design.

1 Claim, 4 Drawing Sheets---
